CLAIM

The ornamental design for an adjustable eyeglass mount for a head set, as shown and described.

DESCRIPTION

FIG. 1 is a top perspective view of an adjustable eyeglass mount for a head set showing my new design; FIG. 2 is a side perspective view thereof in a closed position;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

The broken lines disclosed in FIG. 1 have been shown for illustrative purposes only.
